Fig. 6

FIGURE 1 is a front, top and left end perspective view of an intercom unit, showing my new design;

FIGURE 2 is a side elevational view, to an enlarged scale, the opposite side being substantially a mirror image thereof;

FIGURE 3 is a top plan view, to an enlarged scale;

FIGURE 4 is a rear elevational view, to an enlarged scale;

FIGURE 5 is a bottom plan view, to an enlarged scale; and

FIGURE 6 is a fragmentary cross-sectional view thereof, to an enlarged scale, taken on line 6—6 in FIGURE 2.

The dominant features of my new design reside in the portions shown by means of full lines in the drawings. The grille fragmentarily shown is continuous within the boundaries indicated.

I claim:

The ornamental design for an intercom unit, as shown and described.
